UNITED STATES PATENT OFFICE.

JOSEPH HERMAN, OF SOUTH BARTONVILLE, ILLINOIS, ASSIGNOR TO KEYSTONE STEEL & WIRE COMPANY, OF PEORIA, ILLINOIS, A CORPORATION OF ILLINOIS.

AUTOMATIC WIRE-GAGE AND DETECTOR.

1,141,707.

Specification of Letters Patent.

Patented June 1, 1915.

Application filed July 8, 1912. Serial No. 708,307.

To all whom it may concern:

Be it known that I, JOSEPH HERMAN, a citizen of the United States, residing at South Bartonville, in the county of Peoria 5 and State of Illinois, have invented a new and useful Automatic Wire-Gage and Detector, of which the following is a specification.

This invention has reference to an automatic wire gage and detector, and is adapted for use in the drawing of wire to automatically detect when the wire or rod which is being drawn through the drawing plate or die, is irregular in size or of a larger gage 15 than that for which the apparatus is set, and in so detecting the variance in size of the drawn wire, will produce a sharp crimp in the wire and cause the same to break, thereby automatically notifying or calling to 20 the attention of the operator or wire drawer that the wire being drawn is irregular.

In the process of drawing wire, owing to the imperfections in the plates or dies having the openings through which the wire 25 may be drawn, said openings will wear large and cause the wire which is being drawn, to be irregular in size; in other words, the openings in the plates or dies determine the gage of the wire drawn and if these openings wear large in the operation of drawing the wire, the gage will vary, unless promptly detected by the operator or wire drawer.

The rod bundles contain from two to three hundred pounds and it not unfrequently 35 happens that the operator or wire drawer after setting his plate or die, will not gage the wire drawn until after the drawing of the complete bundle. It is obvious that if the opening in the plate or die through 40 which the wire is drawn should wear very fast, that the wire drawn will be one gage at one end and a different gage at the other end; in fact, it often happens that the opening in the plate or die will wear so large and 45 so fast, that the wire in the bundle will vary from a half to a full gage.

With my improved automatic wire gage and detector, the responsibility is taken from the operator or wire drawer and the change 50 in the gage of the wire drawn is instantly and automatically detected, and the wire

will break, calling to the attention of the operator or wire drawer that the opening in the plate or die through which the wire is being drawn, is wearing, and he will at once 55 stop his block and readjust his plate and draw the wire through a new opening.

In the drawings forming a part of this description, Figure 1 is a plan view of a part of a wire drawing bench and block thereon, 60 and the plate or die stand, with my improvements applied thereto; Fig. 2 is an elevation of the plate or die stand with my improvements applied thereto; Fig. 3 is a cross section as the same would appear if taken on 65 the line 3—3 of Fig. 2, and showing a part of a wire or rod being drawn through the plate or die; Fig. 4 is a detail view of a portion of the plate or die and one of the openings therein through which the wire is being drawn, and showing the wire gage and 70 detector in its normal position and during the time when the wire drawn is of unchanged gage; Fig. 5 is a detail of the wire gage and detector showing the position 75 of the parts at that moment when the opening in the plate or die through which the wire is being drawn, wears large, when the detector will put a sharp crimp in the wire and when any further strain incident to 80 the wire drawing operation occurs, will cause the wire to break, and Fig. 6 is a sectional detail through the detector member showing the manner of supporting the gage 85 block therein.

Like numerals of reference indicate corresponding parts throughout the figures.

1 designates the drawing bench, which, it will be understood supports a great number of drawing blocks, and on said bench is 90 shown the drawing block 2, keyed to the short shaft 3 which may be driven in any suitable manner and upon which the drawn wire is wrapped or coiled, said drawing block being the power means for drawing 95 the wire through the plate or die, said wire or rod, prior to its being drawn, being carried upon a reel or other suitable support.

On the bench and in suitable relation with the wire drawing block is the plate or stand 100 4 in which may be removably and adjustably carried, the plate or die 5. The bench,

the wire drawing block, and the main body portion of the plate stand as well as the plate or die supported therein, are of the usual and well known construction. The plate stand 4 is provided with vertically alined openings 6 and 7, see Figs. 2 and 3, and with the transverse opening 8, see Fig. 3. The plate or die 5 is carried in the opening 8 of the plate stand 4 and rests upon a block 9, of which substitutes of various sizes are provided, whereby the plate or die 5 may be raised or lowered in the plate stand 4, and said plate or die 5 is firmly held in the stand and on the block 9, by means of the screw 10, and in the manner shown in Fig. 3. Said plate or die 5 is provided with a plurality of openings 11 and said openings may be arranged in any suitable manner in the plate or die 5, and may be of uniform diameter or vary from each other in diameter. That is to say, said openings 11 may be all of one gage whereby only one gage wire may be drawn through the plate or die, or they may be of varying gage, whereby various gages of wire may be drawn through the same plate or die. It being understood, that whatever gage of wire is desired to be drawn, that the plate having the desired gage opening or openings is adjusted in the plate stand 4 and the wire inserted and drawn through the desired opening in said plate or die, and said opening, through which the wire is drawn, will determine the gage of the wire and it is desirable that when the plate or die 5 is set and the wire is drawn, that the gage of said wire shall not vary in the length thereof.

At the upper end of the plate stand 4 and projecting from the rear face thereof are ears 11^a, producing a bifurcation in which is carried the arm or member 12. Said arm or member 12 is provided with the tennions 13 journaled in the ears 11^a, whereby the arm or member 12 has a pivotal relation with the ears 11^a. Centrally of the arm or member 12 is provided the opening 14 therethrough, in which is carried the elongated tubular member or sleeve 15, bolts 15^a or other suitable securing means being provided and adapted to be passed through the arm or member 12 for securing the tubular member or sleeve 15 in the arm 12.

Telescopically carried in the tubular member or sleeve 15 is a rod 16, which, at its lower end is bifurcated, producing the ears 17. Carried in the bifurcation of the rod 16, and having a pivotal relation with the ears 17, is a block 18, said block being pivoted to said ears by means of the pivot screws 19. This block 18 is formed with the interiorly disposed recess 20, which opens out of the upper edge of the block and which at its upper end and for a suitable depth, extends across the entire width

of the block, see Fig. 6; the remainder of said recess being preferably rectangular in shape to receive a gage 21 which is adapted to be seated in the recess and which is provided with the opening 22 disposed centrally therein and when said gage is in the recess in the block 18, said opening 22 is in alinement with the axis of the pivot screws 19. The recess 20 communicates with slotted openings 23 in the opposite flat faces of the block 18, see Figs. 2, 4 and 5, and said slotted openings extend from the top of the block to a suitable point below the opening 22 in the gage to give plenty of clearance way to the wire or rod passing through so the opening 22 in the gage.

The gage 21 embodies the features of being removable and adjustably carried in the block 18; being removable that other gages may be substituted so as to change the size of the opening 22 to conform substantially to the opening 11 in the plate or die 5 through which the wire is being drawn, and said gage is adjustable so that the gage may be turned to present an unworn face in case of any wear at any point in the opening 22 in the gage. The gage 21 after being inserted into the recess 20, is firmly held therein by the plate 24, which is inserted into the larger portion of the recess 20 and securely held therein by means of the securing screws 25. To remove the gage 21 to substitute therefor a gage with a larger or similar sized opening or to change the position of the gage 21 in the block 18, the plate 24 is removed.

26 denotes a rod or bar, which is secured to the ears 17 of the rod 16 extending transversely of the bifurcation in the said rod and at a point slightly above and to one side of the center of the pivot screws 19, which pivotally hold the block 18 and the gage in the bifurcation in the end of the rod 16.

In Figs. 3 and 4, the normal position and relation of the block 18 and the gage therein with the plate or die 5, is shown. In this position, it will be observed that the plate or die 5 is adjusted with one of the openings 11 in alinement with the opening 22 in the gage 21, and as said gage is in a perpendicular position with relation to said plate or die and the opening 11, which coincides and is in alinement with the opening in the gage, a wire or rod, as it is drawn through the opening 11 in the plate or die 5, is carried in a straight line through the opening 22 in the gage 21 and said gage under normal conditions, assumes a perpendicular position with respect to the horizontal movement of the wire or rod through the plate or die, and said gage will be maintained in such relation so long as there is no wear to the opening 11 in the plate or die through which the wire or rod is drawn. It will be observed, however, that there is a little play

between the face of the block 18 and the rod or bar 26, when the parts are in the position shown in Figs. 3 and 4. This will allow of a slight oscillatory movement of 5 the block 18 and the gage 21, in the event of any irregularity of the position of the opening 11 in the plate or die 5.

During the operation of drawing a wire or rod, if there is no wear of the wall of the 10 opening 11, or if said opening 11 does not wear large, owing to the drawing operation, the block 18 and the gage 21 will be retained in the normal perpendicular relation to the die or plate 5, as shown in Figs. 3 and 4, 15 by means of the spring 27 yieldingly holding the parts in position shown, with the flat face of the block 18 against the flat face of the plate or die 5. That instant when the wall of the opening 11 in the plate or 20 die 5 begins to wear so that the wire or rod will draw larger than intended, the gage 21 will detect such enlargement of the opening 11 in said plate or die; however, it will be understood that the opening 22 in the gage 25 21 is only large enough to allow free passage of a wire or rod therethrough, and corresponds approximately to the opening 11 in the plate or die through which the wire or rod is being drawn, and the wear of the 30 opening 11 in the plate or die will naturally increase the size of the wire or rod and such increase in size of the wire or rod will not pass through the opening 22 in the gage 21; and the further drawing upon said wire or 35 rod through the frictional engagement of the same with the wall of the opening 22 in the gage 21, will cause said gage and the block in which it is carried, to be moved outwardly and away from the plate or die 5, 40 such movement being permitted owing to the pivotal support for the rod 16 on the upper end of the plate stand, as described.

As the gage and block carrying the same move away from the plate or die 5, the rod 45 16 will move through the tubular member or sleeve 15. It is at this time when the gage 21 and the block 18 are moved outwardly and away from the plate or die 5 through the enlargement of the wire or rod, 50 owing to the wear of the wall or opening 11 in said plate or die, that the rod or bar 26, previously referred to, performs its function or is brought into play. Said rod 26, during the movement of the gage 21 away from the 55 plate or die, is intended to maintain the block 18 and the gage 21 in approximately the same position relative to the rod 16 to which the same is pivoted, as they are in their normal position, when the block 18 is 60 in juxtaposition to the plate or die 5.

In the normal position of the block 18 and the gage, as shown in Figs. 3 and 4, the rod 16 is inclined toward the plate or die 5, from the upper to the lower end thereof, but 65 when the block 18 and the gage is moved

away from the plate or die 5 through the enlargement of the wire or rod, said rod 16 is inclined away from said plate or die 5, from the upper to the lower end of said rod, 70 see Fig. 5; and maintaining the same relation between the block 18 and the rod 16 in such latter position will cause the block 18 to assume an oblique position with respect to the longitudinal movement of the wire or rod and kink said wire or rod as at 28, 75 and the further strain upon the wire or rod in the drawing operation, will break the same and such breaking will indicate to the operator or wire drawer that the opening 11 in the plate or die 5 is wearing. 80

The rod 16 is yieldingly held in the position shown in Figs. 3 and 4, with the block 18 in the normally perpendicular position relative to the line of travel of the wire or rod, by means of a spring 27, the opposite 85 ends of which are coiled about the trunnions 13 of the arm 12 with the terminals of the spring bearing upon the upper face of the stand 4, while the body portion of the spring indicated as 29, extends across and bears 90 against the tubular member or sleeve 15.

One of the many advantages to be derived from the use of my automatic wire gage and detector, is extending the life of the plate or die 5. This may be explained 95 as follows: Assuming that my invention is now applied to a drawing bench or in connection with a plate stand which carries the plate or die 5, and supposing that we are drawing a No. 5 rod down to a No. 8 wire; 100 if the opening 11 in the plate or die 5 begins to wear very rapidly and the same is not detected by the operator or wire drawer, the size of said opening when the drawing operation has been completed, may wear to 105 almost the size of the rod which is being drawn. Such extremely rapid wear is caused by the improper setting up of the opening or openings in the plate, and if such wear is not detected before the opening wears so large, the trouble and expense incident to rebattering the plate or die, precludes the possibility of long use of the plate. On the other hand, with my invention 110 the smallest amount of wear of the 115 plates or dies is quickly and instantly detected and the resetting of the opening or openings in the plate is an easy matter and long life of the plate is insured.

In the operation of drawing wire from a 120 bundle of rods, if the plate or die wears, and the operator or wire drawer does not detect the irregularity or change in the size of the wire the manufacturer will lose a 125 certain number of lineal feet of wire, which he would otherwise obtain with a perfect plate or die; so that, with the use of my device the manufacturer is absolutely assured that he will obtain all the lineal feet 130 of wire from a bundle of rods that he is en-

titled to from the size of opening in the plate or die, whether the plate or die wears or not. There is a further advantage with the use of my device and that is in the 5 quality of wire drawn which may be subsequently used in nail making. It will happen that the plate or die will wear in a manner as to cause the wire to be checked or formed with ridges. Such wire will not 10 make good nails and my device will prevent the wire from being checked or ridged as the wire so drawn will not pass through the gage, but will be detected and broken in the manner described.

15 What I claim is:—

1. In a device of the character described, and in combination with a stand, adapted to support a plate or die; a wire gage, a block for holding the gage, a support having a pivotal connection with said stand, a member having a slidable relation with said support, said block having a pivotal connection with said member.

2. In a device of the character described, and in combination with a stand, adapted to support a plate or die; a wire gage, a block for holding the gage, an arm pivotally connected to said stand, a tubular member or sleeve carried by said arm, a member loosely 30 carried in said tubular member or sleeve, said block having a pivotal connection with said member.

3. In a device of the character described, and in combination; a stand, a plate or die supported thereon; a wire gage, a support for the gage, means for supporting said support on said stand, and means for yieldingly holding the said support in a position so that the gage will be normally maintained 40 in a vertical position and adjacent said plate or die.

4. In a device of the character described, and in combination, a stand, a plate or die supported thereon; a wire gage, a block for supporting said gage, an arm having a pivotal connection with said stand, means carried by said arm for supporting said block, and a spring carried by the arm and engaging the supporting means for the block, for 50 yieldingly holding said block normally in a vertical position and adjacent said plate or die.

5. In a device of the character described, and in combination, a stand, a plate or die supported thereon; a wire gage, a holder for the gage, a rod, and means for pivotally connecting the holder to said rod, a support for the rod, said support being journaled to said stand, and means for normally holding 60 said rod in a position with the flat face of said holder adjacent said plate or die.

6. In a device of the character described, and in combination with a stand, adapted to support a plate or die; a wire gage, a holder for said gage, a rod having a bifur-

cated end, means for pivotally supporting said holder in the bifurcated end of said rod, a support for said rod, and means for pivotally connecting said support to said stand.

7. In a device of the character described, and in combination with a stand, adapted to support a plate or die; a wire gage, a holder for said gage, the opposite walls of the holder being slotted from one outside edge to a point beyond the opening in the 75 gage, a rod, and means for pivotally connecting the holder to said rod, a support for the rod, and means for pivotally connecting said support to said stand.

8. In a device of the character described, a wire gage, a holder for said gage, said holder having a recess to receive the gage, means also adapted to be carried in the recess of the holder for locking the gage in the holder, a pivotally mounted support for the 85 holder, and means for pivotally connecting said holder to said support.

9. In a device of the character described, and in combination with a stand, adapted to support a plate or die; a wire gage, a holder 90 for said gage, a support for said holder including an arm pivotally connected to the stand, said arm having an opening therethrough, a tubular member or sleeve carried in the opening in the arm, means for fixing 95 said tubular member or sleeve in the opening of said arm, a rod loosely carried in said tubular member or sleeve, and means for pivotally connecting the holder to said rod.

10. In a device of the character described, and in combination with a stand, adapted to support a plate or die; a wire gage, a holder for said gage, a rod having spaced ears at one end forming a bifurcation, means for pivotally connecting said holder between the 100 ears and in the bifurcation of said rod, a bar carried in the bifurcation of the rod and connected to the ears thereof, and a support for said rod, said support pivotally connected to said stand.

11. In a device of the character described, and in combination with a stand, adapted to support a plate or die; a wire gage, a holder for said gage, a rod having spaced ears at one end forming a bifurcation, pivot screws 115 for connecting the holder to the ears of the rod and in the bifurcation thereof, a bar carried in the bifurcation of the rod and connected to the ears thereof, a tubular member or sleeve in which said rod is carried and 120 has longitudinal movement and an arm for supporting said tubular member or sleeve, said arm being pivotally connected to said stand.

12. In a device of the character described, 125 in combination, wire drawing means, a gage member having an opening through which a wire may pass, a support adapted to normally hold the gage member adjacent said wire drawing means and approximately 130

- perpendicular to the line of travel of the wire, said gage member being adapted to break the wire at the moment when said wire is being drawn too large to pass through the opening in the gage.
13. In a device of the character described, in combination, wire drawing means, a gage member having an opening through which a wire may pass, a support for the gage, said support being pivotally mounted, means for yieldingly holding the support in a position so that the gage member is normally adjacent said wire drawing means, and means for normally holding the gage in a position perpendicular to the line of travel of the wire, said holding means acting to cause the gage to break the wire, when said wire is being drawn too large to pass through the opening in the gage.
14. In a device of the character described, in combination, wire drawing means, a gage member having an opening through which a wire may pass, a support for the gage, means for pivotally connecting said gage member to said support, means for pivotally mounting said support, means for yieldingly holding the support with the gage member adjacent said wire drawing means, means on the support for maintaining the gage member in a normally perpendicular position relative to the line of travel of the wire, when said wire is being drawn of uniform gage, said last mentioned means acting to cause the gage member to break the wire when said wire is drawn too large to pass through the opening in said gage.
15. Wire drawing means, a gage member having an opening through which a wire may pass, a support for said gage member, means for pivotally mounting said support, said support, when the wire is being uniformly drawn, being adapted to hold the gage member in a position to adapt the drawn wire to pass freely through the opening in the gage member, and means for maintaining the relative positions of gage member and said support, when said support is oscillated through the enlargement of the wire being drawn, and the failure of said enlarged part of the wire to pass through the opening in the gage member, resulting in the breaking of the wire.
16. Wire drawing means, a gage member having an opening through which a wire may pass, a support for said gage member, means for pivotally mounting said support, said support being adapted to hold the gage member adjacent said wire drawing means so that the wire when uniformly drawn will pass freely through the opening in the gage member, means on the support and adjacent the gage member to hold the gage member normally in a position to allow the free passage of the wire therethrough, said holding means being adapted when the support is oscillated, and the gage member is moved from its normal position, to cause the gage member to kink and break the wire.
17. Wire drawing means, a gage member having an opening through which a wire may pass, a holder for the gage member, said holder arranged for the passage of wire therethrough, a support for said holder, said support being pivotally mounted, means for pivotally connecting the holder to said support, means for yieldingly holding the support with the gage and its holder in a position for the passage of drawn wire through the same, means on the support to hold the gage and holder in a position to allow the free passage of drawn wire therethrough, when the drawn wire is uniform, said holding means being adapted when the gage and holder are moved, owing to irregularity of gage in the wire, to bear against the holder and cause the wire passing through the gage to be kinked and broken.
18. Wire drawing means, a gage member having an opening through which a wire may pass, a holder for said gage, a support for said holder, means for pivotally connecting said holder to said support, means for pivotally mounting said support, means for yieldingly holding the support inclined in the direction of the wire drawing means and for positioning the gage and holder adjacent said drawing means, means on the support for holding the gage and said holder normally perpendicular relative to the travel of the wire, said holding means on the support, being adapted when the support is moved into a position inclined from the drawing means, to bear on the gage holder, and cause said gage to kink and break said wire.
19. In a device of the character described, in combination, a wire drawing plate, a wire gage detector, means for supporting said gage adjacent said plate so as to adapt the gage to detect any irregularities or changes in the size of the drawn wire because of any defection in said plate, and to break said wire at the instant such defection or irregularities appear.
20. In a device of the character described, in combination, a wire drawing plate, a wire gage detector, means for supporting said gage in a position for the drawn wire to pass therethrough as it leaves the plate, said gage being adapted to break the wire in case of defection in the drawing plate.
21. In a device of the character described, in combination, a stand, a wire drawing plate mounted on said stand, a wire gage detector, a block for holding said gage, said block being pivotally supported in front of said plate to hold the gage in a position so that the drawn wire will pass through the

same as it leaves the plate, said gage being adapted to break the wire in case of deflection in the drawing plate.

22. In a device of the character described, 5 in combination, a stand, a wire drawing plate mounted on said stand, a gage having an opening to receive a wire, a block formed with a recess to receive the gage, a support for the block, said support adapted to nor-

mally sustain said block in a position so 10 that the drawn wire will pass through the opening in the gage as it leaves the plate, said gage being adapted to break the wire in case of deflection in the drawing plate.

JOSEPH HERMAN.
